UNITED STATES PATENT OFFICE.

FRANK M. SCHAEFER, OF CHICAGO, ILLINOIS, ASSIGNOR TO FRED N. BAYLIES, OF CHICAGO, ILLINOIS.

MEAT-BLOCK.

1,122,314.

Specification of Letters Patent. Patented Dec. 29, 1914.

Application filed March 31, 1913. Serial No. 757,823.

To all whom it may concern:

Be it known that I, FRANK M. SCHAEFER, a citizen of the United States, and a resident of the city of Chicago, in the county of Cook and State of Illinois, have invented certain new and useful Improvements in Meat-Blocks; and I do hereby declare that the following is a full, clear, and exact description of the same, reference being had to the accompanying drawings, and to the numbers of reference marked thereon, which form a part of this specification.

Meat blocks when in use, soon become worn with the constant chopping of the cleaver thereon, and heretofore repair thereof, except by the purchase of a new block, has been difficult. Furthermore, such blocks after used for a comparatively short period of time, become unsightly.

It is an object of this invention to afford a meat block comprising a base having removably seated therein, and rigidly engaged thereto, an upper facing of wood or other suitable material, which may be at any time readily removed to be repaired or dressed, and which, owing to the small quantity of wood required for its construction, may at any time be replaced at small cost.

It is an object of the invention to afford a construction whereby the wooden facing of the block may be very quickly removed from place, and to afford an exceedingly rigid, strong and heavy base constructed to permit such rigid support and quick detachment.

Other important objects will be evident from the description.

In the drawings: Figure 1 is a central vertical section of a device embodying my invention. Fig. 2 is a section on line 2 of Fig. 1. Fig. 3 is an enlarged front elevation showing in detail the mounting for the wrapping material. Fig. 4 is a section taken on line 4—4 of Fig. 3.

As shown in the drawings: 1, indicates the pedestal or base, preferably of molded concrete or cement, reinforced and protected by the metallic rings A, B, and C, respectively. As shown, the pedestal is round, though, of course, not necessarily so, and is provided in its top with a recess in which fits the cutting block, of any suitable material, but preferably wood, indicated as a whole by 2. As shown, the cutting block is made up of strips of wood 3, 4, 5, 6, and 7, and extend-

ing slidably therethrough are metallic rods 8, which extend through eye bolts 9, the heads of which are countersunk into the under side of said cutting block, and the lower or threaded ends of which extend outwardly through the block, which is recessed to afford a flat seat for the nuts 10, on said bolts.

Conveniently, apertures may be provided in the concrete rim of the base or pedestal, to permit of adjustment of said rods 8, after the bolts have been loosened, or to retract said rods to permit the block to be removed from the base or pedestal, as preferred, although this is not necessary or essential inasmuch as the bolt apertures in the pedestal may be slightly slotted at the upper end to permit the blocks, with its eye bolts attached thereto, to be lifted therefrom when the nuts are removed, as indicated in dotted lines in Fig. 1.

The pedestal 1, is recessed at a convenient point in the side thereof and a stud shaft 11, is pivoted to swing therein upon the hinge member 12, which is secured on one wall of said recess. Secured on the opposite wall thereof is a recessed bearing bracket 13, adapted to support the end of the stud shaft 11, and mounted thereabove for the purpose of releasably retaining the shaft end in the recess in the bracket, is a spring member 14. A roll of paper 15, may be slipped over said stud shaft by swinging the same outwardly from the recess and wrapping material is thereby conveniently accessible.

The operation is obvious from the construction described, and obviously the cutting face may be renewed or repaired, as desired, or a new cutting block substituted very quickly when necessary.

Although I have shown the construction as circular, it is, of course, to be understood that any desired conformation of the pedestal or cutting block may be used, and if desired the bolts 8 and 9, may be omitted, thus affording a reversible block, and that other details of construction may be varied without departing from the principles of this invention.

I claim as my invention:

1. A meat block, embracing a pedestal, an imperforate cutting block on said pedestal, and locking means for said block passing through the sides of said pedestal and engaging the bottom of said cutting block, said

locking means adapted to be inserted and removed through the top of said pedestal.

2. A meat block, embracing a pedestal having a recess in the top thereof, a cutting block fitting in said recess, and locking means for said block passing through the sides of said pedestal and acting to retain said block in said recess.

3. A meat block, embracing a pedestal having a recess in the top thereof, a cutting block fitting in said recess, rods slidably extending through said block, eye bolts engaged in the under side of said block and

through the eyes of which said rods pass, said eye bolts extending through diagonally 15 disposed apertures opening through the sides of said pedestal, and nuts on said bolts engaging said pedestal for holding said block in the recess in the pedestal.

In testimony whereof I have hereunto subscribed my name in the presence of two subscribing witnesses.

FRANK M. SCHAEFER.

Witnesses:

CHARLES W. HILLS, Jr.,
LEON M. REIBSTEIN.
